UNITED STATES PATENT OFFICE.

JOSEPH K. KABALAN, OF JERSEY CITY, NEW JERSEY.

DESIGN FOR A SHAWL.

Application filed August 6, 1924. Serial No. 10,391. Term of patent 3½ years.

To all whom it may concern:

Be it known that I, JOSEPH K. KABALAN, a citizen of the United States of America, residing at Jersey City, county of Hudson, and State of New Jersey, have invented a new, original, and ornamental Design for a Shawl, of which the following is a specification, reference being had to the accompanying drawing, forming part thereof.

The figure is a front view of one half of a shawl showing my new design, the design being repeated on the side folded under.

I claim:—

The ornamental design for a shawl as shown and described.

JOSEPH K. KABALAN.
